(57) **CLAIM**

The ornamental design for a box for dental instruments and parts set, as shown and described.

DESCRIPTION

FIG. 1 is a top perspective view of the closed box element of a box for dental instruments and parts set showing our new design;

FIG. 2 is a bottom perspective view thereof;

FIG. 3 is a front plan view thereof;

FIG. 4 is a top plan view thereof;

FIG. 5 is a right side view thereof;

FIG. 6 is a rear plan view thereof;

FIG. 7 is a bottom plan view thereof;

FIG. 8 is a left side view thereof;

FIG. 9 is a top perspective view of the opened box element shown in FIG. 1 of the box for dental instruments and parts set with an insert element;

FIG. 10 is a bottom perspective view thereof;

FIG. 11 is a top plan view thereof;

FIG. 12 is a rear plan view thereof;

FIG. 13 is a left side view thereof with the right side view being a mirror view of the left side;

FIG. 14 is a bottom plan view thereof;

FIG. 15 is a front elevational plan view elevational thereof;

FIG. 16 is a top perspective view of the bottom portion of the box element of the box for dental instruments and parts set shown in FIG. 1 shown with no insert;

FIG. 17 is a bottom perspective view thereof;

FIG. 18 is a front elevational view elevational thereof;

FIG. 19 is a top plan view thereof;

FIG. 20 is a right side elevational view thereof;

FIG. 21 is a rear elevational view thereof;

FIG. 22 is a bottom plan view thereof;

FIG. 23 is a left side elevational;

FIG. 24 is a top perspective view of the insert element of the box for dental instruments and parts set shown in FIG. 9;

FIG. 25 is a top plan view thereof;

FIG. 26 is a rear elevational view thereof;

FIG. 27 is a right side elevational view thereof;

FIG. 28 is a front plan view thereof;

FIG. 29 is a left side elevational view thereof;

(Continued)

FIG. 30 is a bottom plan view thereof;
 FIG. 31 is a top perspective view of another insert element of the box for dental instruments and parts set;
 FIG. 32 is a top plan view thereof;
 FIG. 33 is a rear elevational view thereof;
 FIG. 34 is a right side elevational view thereof;
 FIG. 35 is a front plan view thereof;
 FIG. 36 is a left side elevational view thereof;
 FIG. 37 is a bottom plan view thereof;
 FIG. 38 is a top perspective view of another insert element of the box for dental instruments and parts set;
 FIG. 39 is a top plan view thereof;
 FIG. 40 is a rear elevational view thereof;
 FIG. 41 is a right side elevational view thereof;
 FIG. 42 is a front elevational view thereof;
 FIG. 43 is a left side elevational view thereof;
 FIG. 44 is a bottom plan view thereof;
 FIG. 45 is a top perspective view of another insert element of the box for dental instruments and parts set;
 FIG. 46 is a top elevational plan view thereof;
 FIG. 47 is a rear elevational view thereof;
 FIG. 48 is a right side elevational view thereof;
 FIG. 49 is a front elevational view thereof;
 FIG. 50 is a left side elevational view thereof;
 FIG. 51 is a bottom plan view thereof; and,
 FIG. 52 is an exploded perspective view of the box element shown in FIG. 9 of the box for dental instruments and parts set with another bottom element for the box element with another insert.
 The broken lines immediately adjacent the claimed areas represent the bounds of the claim, and all other broken lines are included for the purpose of illustrating portions of the

present invention that form no part of the claimed design. None of the broken lines form part of the claimed design.
